Application September 5, 1933, Serial No. 688,087

1 Claim. (Cl. 250—27.5)

The present invention relates to the electro-optical transmission and reception of pictures through cathode ray tubes.

The purpose of this invention is to prevent 5 image distortion and to obtain greater luminous intensities.

The basic feature of this invention consists of a method of electronic scanning whereby an image may be dissected into elemental areas 10 formed by independent conducting elements.

A feature of the transmitter is a nonconducting partition imbedded with conducting elements, said partition dividing the cathode ray tube into two sections, an electron chamber, where 15 scanning occurs and a gas chamber where the photoelectric charges are collected.

Another feature of the transmitter provides screening means in the electron chamber to focus the sweeping beam of electrons for each elemental area, after the beam has been deflected. 20

Another feature of the transmitter provides screening means in the gas chamber to collect the photoelectric charges individually and successively in a manner preventing image distortion. 25

A feature of the receiving tube provides means to reproduce visibly each elemental area into an independent luminous gas discharge of substantial intensity. 30

A feature in the electron chamber of the receiving tube prevents image distortion by focusing the sweeping beam of electrons upon each conducting element after deflection of said beam. 35

Another feature in the gas chamber of the receiving tube, provides screening means to modulate the various luminous intensities and to confine each discharge to its respective discharging element. 40

An advantage of the receiving tube is the production of individual and successive concentrated luminous discharges of conducting elements of predetermined symmetrical sizes, the aggregation of these elements forming a luminous image, the intensity of which is suitable 45 for optical magnification and reproduction on a large scale.

An important feature present in the transmitting tube and in the receiving tube, is the symmetrical shaping of the electronic discharge for 50 each elemental area as it is collected by one or several conducting elements, in order to transmit and receive images of a few wide lines or a large number of very fine lines.

Another advantage of the transmitting tube 55 and of the receiving tube is the prevention of

secondary electron emission by the pins which would be contrary in direction and opposing electrical charges and therefore will interfere with the proper scanning action.

The foregoing and other desirable objects are 5 attained in this invention by the new principle disclosed and by the novel feature of construction, combination and relation of parts, herein described and broadly covered in the claim.

The drawing accompanying and forming part 10 of this specification wherein Figure 1 is a diagram for a transmitting system and Figure 2 represents a receiving system is illustrative in character and it is understood that the parts or their relations may be changed in various ways, 15 all within the true intent and scope of this invention.

The well known fluorescent cathode ray tubes used up to date for television purposes, usually 20 do not produce sufficient light for enlarged projection. The sweeping beam of electrons in these tubes must be focussed to a very fine point to prevent the distortion of each pictorial element. This is rather difficult to accomplish in a satisfactory manner as the cross sectional area of the 25 beam varies as it is modulated and also when it is deflected.

In this invention the beam of electrons is not modulated and its cross sectional area is kept 30 constant, thus distortion effects due to spreading of electrons or variations in sizes of elements are prevented.

The individual isolation of each conducting element furthermore prevents the overlapping distortion effects of adjacent elements. 35

The fact that the sweeping beam of electrons carries current from the heated cathode in the electron chamber to the screen anode in the gas chamber, enables these devices to commutate 40 concentrated, high negative potential charges upon the surface of the conducting elements and thereby cause greater voltage variations of the transmitting tube, and intense concentrated luminous discharges at the receiving tube.

Fig. 1 in the drawing is a schematic illustration 45 of the transmitting system where (1) is an illuminated surface, (2) is an optical lens system projecting the image light rays reflected from the subject upon a plurality of conducting elements or pins (4) coated with photoelectric substances and imbedded in a non-conducting partition (3) which divides a cathode ray tube (23) into a light sensitive chamber (5) and a cathode ray scanning chamber (8). The image is projected upon the photoelectric surfaces of pins 50 55

(4). These pins emit electrons in proportion to the amount of light they receive. One pin or a group of pins may be connected at a time by the scanning beam of electrons sweeping over their conducting surfaces (4A) exposed in the scanning chamber.

When the beam of electrons impinges upon the end of a pin or a group of pins, at (4A), for example, the negative charge thus imparted to these pins establishes a difference of potential between their surfaces in the photo electric chamber (5) and the anode screen (6) facing them. Thus an electric current is enabled to flow from source (17) through a coupling load resistance (15) then from screen (6) at point (4B), for example, and the pin or group of pins at point (4A) being in contact with the scanning beam of electrons. The electrical circuit is then completed through the beam of electrons (9), the cathode (13) which emits them and the negative side of potential source (17). The various amounts of electrons emitted by the photo electric surfaces of pins (4) in chamber (5) causes increases or decreases of the current transferred through the scanning beam of electrons and thereby causing voltage drops in coupling resistor (15), said variations being transferred electrostatically through condenser (19) connected to a thermionic vacuum tube amplifier (20) which has its control grid biased by a battery (18) and a current limiting resistor (16). The voltage variations amplified are transferred to the transmitter proper which radiates the image's signal.

Deflecting plates (10), perforated accelerating anode (11) and the negative cylinder (12) are of standard design as are now well known in the art.

The receiving system as illustrated in Figure 2 consists of an electronic discharge device system similar in construction to the cathode ray tube previously described in the specifications except that gas chamber (35) contains in this case a luminous producing gas and that the ends of the pins exposed in this chamber have not photoelectric properties. The image signal received is magnified by a selective amplifying receiving system (60). The last stage of amplification comprising a power tube is shown at (50). The signal voltage variations delivered by the output circuit of this tube are transferred electrostatically through condenser (49) modulating the voltage of anode screen (36).

Both cathode ray tubes operating in exact synchronism, the group of pins commutated by the scanning beam of electrons at any particular moment will acquire a negative charge. This causes an electric current to flow from the anode screen (36) to the pins (34) and the commutating beam of electrons. Due to the fact that chamber (35) contains luminous ionizable gases or vapors, a luminous glow discharge takes place between the pins commutated and the screen 10 anode.

Screen (37) in the scanning chamber is charged with a small negative potential which serves the purpose of further reducing the cross sectional area of the scanning beam of electrons. This feature of my invention is also used to reduce secondary emission effects from the ends of the pins in the scanning chamber which otherwise would interfere with the proper sequence and distribution of electrons from the scanning beam and the various pins. Screen (37) serves also the purpose of varying the size of each elemental pictorial area and thereby may be used to control the sharpness of definition of the image. Each luminous discharge corresponding to the pictorial element, equals approximately in area the cross section of the electron beam near the surface of pins (34) in the scanning chamber and is very small, however, the glow discharge may, under favorable conditions, be very intense as it is the result of a highly concentrated electrical discharge in the particular area.

I claim:

A cathode ray device for receiving signal energy for transformation into picture images comprising a first evacuated chamber, a second chamber containing a light-producing gas, an insulating partition separating said chambers and having a plurality of conductive elements embedded therein forming a scanning mosaic, each of said elements forming a conducting path connecting said chambers, means for producing an electron beam in said first chamber for scanning said mosaic, a metallic grid in said first chamber disposed opposite said mosaic and electrically charged to focus the electron beam upon the several elemental areas of said mosaic, and a grid-like anode in said second chamber disposed close to and opposite said partition.

LUIS A. LORA.
